UNITED STATES PATENT OFFICE.

WILLIAM D. SNYDER, OF CHICAGO, ILLINOIS, ASSIGNOR TO THE FORT WAYNE FURNITURE COMPANY, OF FORT WAYNE, INDIANA.

FOLDING BEDSTEAD.

SPECIFICATION forming part of Letters Patent No. 417,108, dated December 10, 1889.

Application filed June 27, 1889. Serial No. 315,841. (No model.)

To all whom it may concern:

Be it known that I, WILLIAM D. SNYDER, of Chicago, in the county of Cook and State of Illinois, have invented certain new and useful Improvements in Folding Bedsteads, of which the following is a specification.

The invention relates to folding or combination cabinet-bedsteads; and the object thereof is to dispense with a counterbalance-weight for the folding frame as commonly used in such bedsteads. This object I have attained by the combination, with the folding frame and stationary frame, of a supplemental frame and an elastic coil-wire bed-bottom, said parts being arranged, as shown, relatively to one another and connected substantially as illustrated in the accompanying drawings, in which—

Figure 1 is a vertical section of a bedstead containing my invention, the bed being closed. Fig. 2 is a like section, the bed being open. Fig. 3 is a rear elevation. Fig. 4 is a front view; and Fig. 5 is a fragmentary side view, with that portion of the side piece of the stationary frame to which the folding frame is attached broken away, showing the working parts enlarged and the manner of their attachment.

By using the folding frame in conjunction with a supplemental frame and an elastic coil-wire bed-bottom and connecting the same with the stationary frame in the manner hereshown the fabric is put under strain by the unfolding or opening of the bed, so that the resiliency thereof may be made to serve as a counter-balance to aid in closing the bed.

The invention is best adapted to be used in that class of bedsteads wherein a dressing-case or book-case is combined with a folding bedstead, the front part of the structure being provided with shelves and drawers adapted to the uses of a book or dressing case, and the folding bedstead fitting into a recess in the back or part which in the daytime is turned to the wall for the reason that in such structures the front portion acts as a counterpoise to the rear portion to prevent tipping over when opening the bed; but the invention is not limited to bedsteads of this class.

In the drawings, A designates the stationary frame, which is constructed on the plan above suggested and has the front part provided with doors A' and drawers A², inclosing compartments, adapting the same to the uses of a commode and dressing-case, and the rear part provided with a recess A³, into which the folding frame B may be lifted.

The folding frame is connected to the stationary frame near the bottom by a rod a, attached on each side to the stationary frame, so as to support the head end of the folding frame when the lower edge thereof is rested on said rod. The lower edges of the side rails of the folding frame where they come in contact with said rod are provided with metal bearings a' and a loop or keeper a², which incloses said rod and prevents the folding frame from being lifted off the same. The joint or connection thus made permits the folding frame to slide endwise on said rod during the folding and unfolding; and there is a link b on each side pivoted at one end to the folding frame at b' near its extreme head end, and at the other end to the stationary frame at b². These links cause the folding frame to slide on said rod or move endwise during the folding or unfolding and support it when in the vertical position.

At the foot end the folding frame is provided with a transverse bar B', which is firmly secured to said frame by means of metal brackets and bolts, and to this transverse bar the foot end of the elastic coil-wire bed-bottom C is attached. The transverse bar B², for supporting said bed-bottom at the head end, is part of a short supplemental frame B³, which is pivotally and endwise-movably secured at its head end to the stationary frame by means of pins c, fastened one to each side of the stationary frame and working in a slot or groove c' in the side bars of said supplemental frame. The opposite end of said supplemental frame is free and comes against a shoulder at c² on each side of the folding frame, when said frame is being unfolded or let down to the horizontal, so that the fabric, which is slack when said folding frame is vertical, is stretched and drawn taut by the weight and downward force.

movement of the foot end during the unfolding, the tension of the fabric being sufficient at the horizontal to support the bed as in an ordinary coil-wire bed-bottom.

5 The transverse bar B^2 may be made adjustable by means of screw-bolts d , arranged in the ordinary way to move said bar slightly in said supplemental frame toward the head or foot for the purpose of regulating the tension of the fabric.

The folding frame is provided with folding foot-legs E , which are pivoted thereto and connected together by cross-pieces e . The foot-legs are connected by a rod e' on one side of the bed with the rod a , the connection being between the upper end of the leg above its pivotal connection with the folding frame and said rod a , so that the endwise movement of the folding frame during the opening and closing of the bed, operating in conjunction with the restriction of the rod e' upon the

legs, causes the legs to be opened and closed in the ordinary manner.

What I claim is—

In a folding bedstead and in combination, 25 a stationary frame provided with a recess for the folding frame, a folding frame connected to the stationary frame by a sliding joint, links pivoted to both of said frames and arranged, as shown, relatively to said sliding joint, a short supplemental frame connected 30 at one end to said stationary frame by a loose joint and having its free or opposite end arranged, as shown, relatively to the folding frame, and an elastic bed-bottom connected 35 to the foot-bar of the folding frame and to a transverse bar of the supplemental frame, as specified.

WILLIAM D. SNYDER.
